UNITED STATES PATENT OFFICE.

CHARLES P. HALL, OF NEAR HIGHLAND SPRINGS, VIRGINIA.

GOVERNOR FOR GAS-ENGINES.

1,394,826.

Specification of Letters Patent.

Patented Oct. 25, 1921.

Application filed September 13, 1920. Serial No. 410,080.

To all whom it may concern:

Be it known that I, CHARLES P. HALL, a citizen of the United States of America, residing near Highland Springs, in the county of Hanover and State of Virginia, have invented certain new and useful Improvements in Governors for Gas-Engines; and I do declare the following to be a full, clear, and exact description of the invention, such as will enable others skilled in the art to which it appertains to make and use the same.

This invention relates to an improved governor for use in connection with a gas engine and one object of the invention is to provide a governor so constructed that after the engine has been started the governor may be employed as means for controlling the feeding of the combustible mixture to the cylinders. The motor will thus be prevented from running beyond a desired speed.

Another object of the invention is to so construct this governor that it can be used in connection with the conventional construction of internal combustion engines, the manually operated rod for opening and closing the valve being disconnected from the valve actuating mechanism after the motor has been started.

Another object of the invention is to so construct the governor that it may be actuated by the belt which operates the cooling fan positioned in front of the motor and between the motor and radiator.

Another object of the invention is to provide a governor which will be very efficient in operation and which will be easy to assemble and install.

This invention is illustrated in the accompanying drawings wherein:—

Figure 1 is a view in side elevation showing the improved governor in position for use in connection with an internal combustion engine.

Fig. 2 is a vertical sectional view through the governor.

Fig. 3 is a sectional view taken along the line 3—3 of Fig. 2.

Fig. 4 is a sectional view taken along the line 4—4 of Fig. 2.

Fig. 5 is a sectional view taken along the line 5—5 of Fig. 2.

Fig. 6 is a sectional view taken along the line 6—6 of Fig. 2.

Fig. 7 is a fragmentary sectional view taken along the line 7—7 of Fig. 2. This governor has been shown in connection with the motor 1 of a tractor and is located between the forward end of the motor 60 and the radiator 2. In a motor of this type it is customary to provide a butterfly valve 3 for the inlet manifold 4, the valve being provided with an actuating stem 5 upon which is mounted a head 6 having sockets 65 formed therein to receive the fork 7 of an actuating rod 8. This actuating rod 8 extends rearwardly to the driver's seat and may be moved longitudinally to bring the fork into and out of the sockets of the head 70 6. It will thus be seen that when it is desired to control the speed of the motor it is customary to turn the valve stem 5 through the medium of this stem or rod 8. As previously stated it is the object of this invention to permit the speed to be automatically controlled thus making it unnecessary to manually operate the valve.

The head 6 of this valve stem 5 is provided with side arms 9 and 9' for engaging 80 an abutment 10 and the side arm 9' carries a screw 11 which is adapted to engage the abutment 10 and thus permits the swing of the butterfly valve to be controlled. A link 12 is connected with the side arm 9' and this 85 link 12 is connected with an arm 13 extending from a rocker shaft 14 having one end portion mounted in the bearing bracket 15 and its second end portion extending forwardly and journaled in the bearings 16 90 provided in the upper portion of the governor housing 17. This governor housing 17 is carried by a base 18 which base is provided with side plates 19 secured to the motor by the securing screws 20. One portion 21 95 of this motor casing 17 is formed separately from the remainder and hingedly mounted as shown at 22 thus providing a door which may be opened when it is desired to have access to the interior of the governor housing.

A web 23 is provided in the base 18 and is provided with a vertically disposed opening 24 having enlarged and threaded upper and lower end portions 25 and 26 thus forming 105 sockets at the upper and lower ends of the passage 24. A shaft 27 fits into the passage 24 and is provided with a collar 28 positioned in the lower portion of the socket 25 and having anti-friction balls 29 positioned 110

thereon and engaged by a gland 30 which is screwed into the socket 25. A plug 31 is screwed into the socket 26 and bearing balls 32 are positioned between this plug and the 5 lower end of the shaft 27. It will thus be seen that the shaft will be permitted a free rotary movement and will be held against longitudinal movement.

A beveled gear 33 is mounted upon the 10 shaft 27 above the gland 30 and meshes with a beveled gear 34 mounted upon a shaft 35 which is journaled in the base and extends beyond the same with its extended forward end portions carrying a pulley wheel 36 for 15 engaging the belt 37 which transmits rotary movement to the fan 38. It will thus be seen that when the motor is in operation the shaft 27 will be rotated by the same belt which drives the fan.

20 In order to permit movement to be transmitted to the rocker shaft 14 this shaft has been provided with an arm 39 which extends into the slot 40 of a head 41 carried by the sleeve 42. This arm 39 is engaged by a pin 25 43 and therefore when the sleeve 42 moves upwardly against the action of the spring 44 the arm 39 will be moved and the rocker shaft thus rotated. This spring 44 is engaged by a compression screw 45 which is 30 threaded through a bearing in the head 46 of the governor housing 17 thus permitting the compression of the spring to be controlled and thereby permitting the action of the governor to be controlled and the governor prevented from operating to shut off the supply of gas to the motor before desired. The sleeve 42 has its lower end provided with a disk 47 which is held in spaced relation to the disk 48 by bearing balls 49. 35 This disk 48 has its under face provided with grooves 50 which are cut to register with grooves or seats 51 formed in the beveled gear 33. The levers 52 are pivotally mounted at the outer ends of the grooves or 40 seats 51 and have their lower arms 53 extending through the seats 51 and provided with upturned ends as shown in Fig. 2 so that when the levers 52 swing outwardly the inner end portions of the arms 53 which fit 45 into the grooves or seats 50 will tend to move the disk 48 upwardly. Therefore the disk 47 and sleeve 42 will be moved upwardly and as previously explained the shaft 14 rotated. Springs 54 are provided as shown 50 clearly in Fig. 7 to normally retain the levers in the position of Fig. 2 but permit them to be swung outwardly by the centrifugal force created when the governor is in 55 operation.

60 When this device is in use it is installed as shown and when it is desired to start the motor the rod 8 will be moved to bring the fork 7 into engagement with the head 6. The head will be turned to open the butterfly valve and the motor started. After the 65

motor has started the rod 8 can be drawn to an inactive position and when the motor is running at a normal rate of speed the butterfly valve will be left in the properly adjusted position. If however, the motor 70 should run at too great a speed the centrifugal force will cause the arms or governor levers 52 to be swung outwardly thus raising the sleeve 42 against the action of the spring 44 and causing the rocker shaft 14 75 to be rotated. This will cause the head 6 to be turned and the valve shut off a sufficient amount to reduce the speed of the motor. The tractor will thus be prevented from being damaged by the motor running at too 80 high a rate of speed. Adjustment of the screw 45 will permit the spring to be placed under any tension desired and thus the governor prevented from operating to reduce the speed of the motor before desired. There 85 has thus been provided a governor which can be associated with the motor of a tractor of a conventional construction.

What is claimed is:—

1. A governor for the purpose set forth 90 comprising a housing, a valve actuating shaft extending transversely of the housing and having one end portion journaled therein and extending through the housing, a shaft rotatably mounted in the housing and positioned vertically therein, a gear carried by the vertical shaft, a drive shaft having a gear meshing with the gear of the vertical shaft, a sleeve slidably mounted upon the vertical shaft, a disk slidably mounted upon the vertical shaft between the gear thereof and the lower end of said sleeve and held against rotation upon the vertical shaft, a head carried by the sleeve and having a slot formed therein, an arm extending from the 100 first mentioned shaft and extending into the slot of said head, a shaft carried by the head and extending through a slot in said arm, bell crank levers pivotally connected with the gear of the vertical shaft and having lower arms extending between the gear and disk mounted upon the vertical shaft, the bell crank levers having weighted upper 110 arms swung outwardly to raise the lower arms by centrifugal force, and resilient 115 means yieldably holding the upper arms against outward movement.

2. A governor for a gas engine valve comprising a housing, a driven shaft rotatably mounted and positioned vertically in the housing, a gear upon the shaft, a sleeve loosely mounted upon the shaft above the gear, a disk carried by the lower end portion of the sleeve, a disk slidably mounted upon the shaft between the gear and disk of said sleeve 125 and held against rotation upon the shaft, weighted levers pivotally connected with the gear and having lower arms extending between the gear and last mentioned sleeve for moving the sleeve upwardly when the 130

- weighted levers are swung outwardly by centrifugal force, means yieldably retaining the levers against outward movement, resilient means yieldably holding the sleeve against 5 upward movement, a valve actuating shaft extending through the housing and having an arm connected with the sleeve, and means for transmitting rotary movement to the vertical shaft through the medium carried thereby.
3. A governor for a gas engine valve comprising a housing, a valve actuating shaft extending transversely through the housing, an arm extending from the shaft, a driven 15 shaft positioned vertically in the housing and rotatably mounted, a sleeve slidably mounted upon the vertical shaft and having said arms connected therewith for imparting rotary movement to the valve actuating shaft when the sleeve moves vertically, a gear carried by the vertical shaft, a disk slidably mounted upon the vertical shaft between the sleeve and gear and held against rotation upon the shaft, the disk and gear being provided with radially extending 25 grooves, levers pivotally connected with the gear and having arms extending through the grooves of the gear and terminating in upturned end portions fitting into the grooves of the disk a spring for yieldably holding the sleeve against vertical movement, means for compressing said spring to retain the same at a predetermined tension, and means yieldably holding said levers 30 against outward swinging movement.
4. A governor for a gas engine valve comprising a housing, a valve actuating shaft extending transversely of and journaled in the housing, an arm extending from the shaft, a driven shaft positioned vertically in the housing and rotatably mounted, a sleeve loosely mounted upon the driven shaft, a gear carried by said driven shaft, a disk positioned between the sleeve and gear, bell 40 crank levers pivotally connected with the gear and having arms extending between the gear and disk, springs connecting the upper end portions of the bell crank levers to yieldably hold the same against outward movement when said gear is rotated, a head carried by the sleeve and having said arms connected therewith, and resilient means positioned in the housing and engaging said head to yieldably hold the sleeve against vertical movement.
5. A governor for a gas engine valve comprising a housing having a base and a body carried thereby and having one section hingedly mounted to provide a door, a driven shaft positioned vertically in the 55 housing and having its lower portion extending into a vertical passage formed in the base, a movable bearing element carried by the base and engaging the shaft to retain the same in the passage of the base, a gear 60 carried by the shaft, a sleeve slidably mounted upon the shaft, a head carried by the housing, an abutment screw carried by the head, a spring positioned between the abutment screw and sleeve and placed under tension by said screw, a valve actuating shaft 65 extending through the housing and having an arm connected with the sleeve for imparting movement to the valve actuating shaft when the sleeve moves vertically, a disk 70 slidably mounted upon the driven shaft between the sleeve and gear and held against rotation upon the driven shaft, weighted levers carried by the gear and engaging the disk to move the same upwardly when the 75 levers are moved outwardly by centrifugal force, and yieldable means retaining the levers against outward swinging movement.
6. A governor for an internal combustion engine valve comprising a housing, a valve 80 actuating shaft, means for connecting one end portion of the shaft with a valve mechanism, an arm carried by said shaft, a driven shaft rotatably mounted in the housing, a sleeve loosely mounted upon the driven shaft 85 for longitudinal movement thereon and having connection with the arm of the valve actuating shaft for imparting rotary movement thereto when the sleeve moves longitudinally, means for imparting rotary movement to the driven shaft including a gear mounted thereon, bell crank levers carried by the gear for imparting sliding movement to the sleeves, means for yieldably holding the sleeve against sliding movement, and 90 means for yieldably holding the bell crank levers against outward movement under the centrifugal force of rotation.

In testimony whereof I have hereunto set my hand.

CHARLES P. HALL.
